WATERPROOF POCKET

Edgar B. Davis, Tangerine, Fla.

Application June 14, 1949, Serial No. 99,048

3 Claims. (Cl. 2-252)

1

This invention relates to pockets or purses, and more particularly to a waterproof pocket to be worn on a bathing suit or swimming garment to protect articles carried by the wearer from water.

It is among the objects of the invention to provide a waterproof pocket which can be attached to a garment, belt or strap for carrying on the person of the wearer, which is of simple and economical construction and is permanently sealed on all edges except at one end, which includes manually-operated means for opening and closing such one end and securely sealing such one end when closed, against entrance of water, and which is extremely durable in use and of neat and attractive appearance.

Other objects and advantages will become apparent from a consideration of the following description and the appended claims in conjunction with the accompanying drawings, wherein—

Figure 1 is a side elevation of a waterproof purse illustrative of the invention, showing the purse in closed condition;

Figure 2 is a side elevation of a fragmentary upper portion of the purse illustrated in Figure 1 showing the purse in open condition;

Figure 3 is a side elevation of a fragmentary portion of the purse showing the purse in closed and folded condition;

Figure 4 is a longitudinal cross-section of a fragmentary portion of the purse and is taken substantially on the line 4—4 of Figure 1;

Figure 5 is a longitudinal cross-section similar to Figure 4 and taken on the line 5—5 of Figure 2, and diagrammatically illustrates the manner in which the top end of the purse is opened to provide access to the interior thereof;

Figure 6 is a transverse cross-section of the purse-closing clamp bar and is taken substantially on the line 6—6 of Figure 2;

Figure 7 is a plan view of a blank of flexible material from which the body of the purse is made;

Figure 8 is a plan view of the material blank at a later stage in the manufacture of the purse, with the blank folded to doubled condition and with its opposite side edges sealed together;

Figure 9 is a longitudinal cross-section on the line 9—9 of Figure 8;

Figure 10 is a transverse cross-section on the line 10—10 of Figure 8;

Figure 11 is a diagrammatic illustration showing the manner of applying the purse to a garment, such as a pair of bathing trunks;

Figure 12 is an elevation of a fragmentary portion of the purse shown on a somewhat enlarged

scale to illustrate the means for locking the purse in closed condition;

Figure 13 is an edge elevation of a fragmentary portion of the purse illustrated in Figure 12;

Figure 14 is an elevational view similar to Figure 12, showing the purse in partly unlocked condition;

Figure 15 is an edge elevation of a fragmentary portion of the purse in the condition illustrated in Figure 14;

Figure 16 is a side elevation of a fragmentary portion of the purse showing the manner of attaching the locking bar to the body of the purse;

Figure 17 is a longitudinal cross-section on the line 17—17 of Figure 16; and

Figure 18 is a view similar to Figure 16, but showing the parts in a different operative position from that illustrated in Figure 16.

With continued reference to the drawings, the improved, waterproof pocket comprises, in general, a body portion 10 of flexible, waterproof material, such as a coated fabric, synthetic or natural rubber, or synthetic resin sheet material, having a pair of tabs 11 projecting outwardly from respectively opposite sides of the body portion, a resilient bar 12 secured to one side of the body portion at one end of the latter, a locking bar or clamp bar 13 pivotally secured at one end to the resilient bar 12 at one end of the latter, and a locking clip 14 pivotally carried by the clamp bar 13 at the opposite end of the clamp bar.

In manufacturing the pocket, a blank is first prepared, as illustrated in Figure 7. This blank is of elongated, rectangular shape and is provided with symmetrically reduced end portions 15 and with outwardly-projecting tabs 16, two of which are disposed adjacent one of the end portions 15, and at respectively opposite sides of the blank, and the other two of which are disposed adjacent the other end portion 15, and also at respectively opposite sides of the blank.

After the blank has been prepared, as illustrated in Figure 7, it is transversely folded at its mid-length position, as indicated by the dotted line 17, so that it is doubled to provide two superimposed, substantially identical side walls 18 and 19, as illustrated in Figures 8 and 9, and these side walls are permanently sealed together along their opposite side edges extending from respectively opposite ends of the transverse fold 17, as indicated by the dotted line 20 in Figure 8. The side walls 18 and 19 of the pocket are then joined together along three edges, but are separate along the transverse edges of the reduced end portions 15 which is the top end of the pocket. The oppo-

55

site side edges of the side walls may be sealed together by any suitable process, such as vulcanizing or cementing and, if desired, a folded spacing tape 21 may be interposed between the two side walls along the opposite, longitudinal edges of such side walls, as particularly illustrated in Figure 10, to maintain the two side walls in slightly spaced-apart relationship and to reinforce the longitudinal edges of the pocket.

Either before or after the longitudinal side edges of the side walls 18 and 19 are sealed together, a resilient bar 12 is secured to one of the side walls at the end thereof remote from the transverse fold 17. This resilient bar 12 is a flat, thin bar of suitable material, such as spring steel, and is preferably coated, plated, or otherwise treated to render it resistant to corrosion. The bar is firmly cemented or vulcanized to the side wall of the body of the pocket so that its outer edge is substantially flush with the outer edge of the corresponding side wall, and, if desired, the material of the side wall may be extended entirely around this bar to provide a protective covering for the same.

The clamp bar 13 is provided, at one end, with a partly circular hinge formation 22 continuous at one end with the bar, and provided, near its opposite end, with an aperture receiving a hinge pin or rivet 23 by means of which the clamp bar 13 is secured to the resilient bar 12, the rivet 23 preferably being disposed near the outer corner at one end of the bar 12. The clamp bar 13 is formed of substantially rigid, thin-walled material, such as a suitable metal, metal alloy, or synthetic resin plastic, and is of U-shaped cross-section, as particularly illustrated in Figure 6. The clamp bar 13 is connected to the resilient bar 12 in a manner such that when the resilient bar is straight with the side wall to which it is attached, as illustrated in Figures 2 and 16, the closed side of the clamp bar 13 would be opposed to the outer edge of the resilient bar 12 if the clamp bar were pivoted over to a position in which it is super-imposed on the outer edge of the resilient bar.

In order to close the open end of the pocket, the resilient bar 12 is rolled one-half-a-turn in the material of both of the side walls 18 and 19 at the open end of the pocket, bringing the material of the free side wall tightly over the resilient bar. This inversion of the resilient bar inverts the relative position of the clamp bar, so that when the resilient bar has been so turned, the open edge of the clamp bar will be opposed to the outer edge of the resilient bar when the clamp bar is pivoted over to a position at which it is super-imposed on the resilient bar.

After the clamp bar has been pivoted over to receive the resilient bar 12 with the end portions of the side walls of the pocket wrapped about such resilient bar, the clamp bar may be releasably locked in such pocket-closing position by the clip 14. This clip is a rectangular member of U-shaped cross-section, one side of which is pivotally connected to the clamp bar 13 at the end of the latter opposite the hinge structure 22, and is pivotally movable between a position in which it embraces the corresponding end of the resilient bar 12, as illustrated in Figures 1 and 12, and a position in which it is disposed outwardly of the end of the resilient bar, as illustrated in Figure 14. A projection 24 is provided on the end of the resilient bar opposite the end of the latter pivotally connected to the clamp bar 13, which projection is at the upper edge of the resilient bar 12.

when the resilient bar has been folded one-half-turn into the material of the side walls of the pocket, this position of the projection 24 being particularly illustrated in Figures 12 and 14. After the clamp bar has been pivoted to its pocket-closing position in which it receives the resilient bar 12 therein, the clip 14 may be pivoted on the end of the clamp bar, so that it engages under the projection 24, as particularly illustrated in Figure 12, to hold the corresponding end of the clamp bar against outward movement relative to the resilient bar. The clip is releasably retained in this locking position by inter-engaging depressions 25 and 26 provided in the clip and the clamp bar respectively, and is movable to its unlocking position, as illustrated in Figure 14, by finger pressure thereon. In its unlocking position, the clip 14 clears the projection 24 when the clamp bar 13 is pivoted outwardly relative to the resilient bar 12.

When the clamp bar has been pivoted outwardly away from the resilient bar 12, the resilient bar may be turned through one-half turn to unfold it from the side wall material at the open end of the pocket, and thereafter the purse side walls may be separated at the open end of the pocket by reason of the resilient nature of the resilient bar 12 and the flexible nature of the opposite side wall, to provide access to the interior of the pocket.

The pocket is preferably made of a size to contain such articles as cigarettes and matches, cosmetic articles, and similar personal property of the wearer.

The pocket may be attached to a garment, such as the swimming trunks 27, particularly illustrated in Figure 11, by sewing the tabs 16 in doubled or super-imposed condition to the material of the garment. The tabs may also be secured to a belt or strap if it is desired to provide the pocket with such means for securing it on the body of the wearer. After the pocket has been closed in the above-indicated manner, and the closing means released, the portion of the pocket above the tabs 16 may be folded over at the upper edges of the tabs to underlie the inner side wall of the pocket between the pocket and the body of the wearer, as illustrated in Figures 3 and 11, so that the fastening means will be protected from accidental displacement. If desired, the inner side wall of the pocket may be provided with a transversely-extending pleat therein to receive the fastening means when in such folded-over condition.

In Figure 11 two pockets are shown attached to the swimming trunks 27, one a large pocket A for holding cigarettes and similar articles, and the other a small pocket B which may be used as a watch pocket. While the construction of the large pocket A has been hereinabove described in detail, the small pocket B is made in exactly the same manner, except for a smaller and somewhat different shape of the original blank of flexible, waterproof material.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A waterproof pocket comprising a generally rectangular piece of flexible, waterproof material transversely folded at its mid-length location to provide two opposite side walls, said two side walls being permanently sealed together along their opposite longitudinal edges extending from the respectively opposite ends of the transverse fold, a resilient bar secured to that edge of one of said side walls which extends between the ends of said sealed edges remote from the transverse fold, a clamp bar of U-shaped cross-section pivotally secured at one end to said resilient bar at one end of the latter, and a clip pivotally secured to said clamp bar at its opposite end, said clamp bar being attached to said resilient bar in a manner such that the open end of said clamp bar is opposed to the outer edge of said resilient bar only after said resilient bar has been wrapped for one-half-turn in said side walls at the end of said pocket at which said resilient bar is attached.

2. A waterproof pocket comprising a piece of flexible, waterproof material folded to provide two opposite side walls, said side walls being sealed together along their opposite longitudinal edges and separate at one end of the pocket, and means providing a waterproof closure of said one end of the pocket comprising a resilient, flat bar extending transversely of and secured to one of said side walls at said one end of the pocket, said resilient bar being turnable through one-half-turn to wrap the material of said side walls and said one end of the pocket around said resilient bar, and a clamp bar of U-shaped cross-section pivotally connected at one end to said resilient bar at one end of the latter and movable relative to said resilient bar when the latter has been turned to wrap the side wall material therearound to embracingly receive said resilient bar and the wrapped side wall material to thereby

maintain the side wall material wrapped around said resilient bar and said one end of the pocket tightly closed.

3. A waterproof pocket comprising side walls of flexible, waterproof material having separate edges along one end of the pocket and the remainder of their edges joined together, and closure means for said one end of the pocket comprising an elongated bar secured to one of said side walls and extending along the edge of the latter at said one end of the pocket, and a clamp bar of U-shaped cross-section pivotally connected at one end to said first-mentioned bar at one end of the latter and movable relative to said first-mentioned bar to embracingly receive the latter with side wall material at the open end of the pocket wrapped therearound, a projection on the end of the first-mentioned bar opposite the end of the latter to which said clamp bar is pivotally connected, and a clip of U-shaped cross-section pivotally connected to said clamp bar at the end of the latter opposite the end pivotally connected to said first-mentioned bar, said clip being engageable with said projection to releasably maintain said first-mentioned bar in said clamp bar.
